DESIGN FOR AN ASH TRAY

Nicholas F. Caputo, Kearny, N. J.

Application January 15, 1946, Serial No. 125,557

Term of patent 3½ years

(Cl. D85—2)

To all whom it may concern:

Be it known that I, Nicholas F. Caputo, a citizen of the United States, residing at Kearny, in the county of Hudson and State of New Jersey, have invented a new, original, and ornamental Design for an Ash Tray, of which the following is a specification, reference being had to the accompanying drawing, forming part thereof.

Figure 1 is a view in side elevation of an ash tray embodying my new design.

Figure 2 is a top plan view of the ash tray shown in Figure 1.

Figure 3 is a view in front elevation of the ash tray shown in Figure 2.

Figure 4 is a view in rear elevation of the ash tray shown in Figure 1.

I claim:

The ornamental design for an ash tray, as shown.

NICHOLAS F. CAPUTO.
